CLAIM

The ornamental design for a removable top for drinking bottles, as shown and described.

DESCRIPTION

FIG. 1 is a perspective view of a removable top for drinking bottles with the cap for the straw hole in its stored location; FIG. 2 is a perspective view of a removable top for drinking bottles in an alternate position with the cap covering the straw hole;

FIG. 3 is a top plan view of FIG.1;

FIG. 4 is a right side elevational view thereof, the left side elevational view being a mirror image thereof;

FIG. 5 is a front elevational view thereof;

FIG. 6 is a rear elevational view thereof; and,

FIG. 7 is a bottom plan view thereof.

The broken line showing of a straw and the base of a drinking bottle in FIGS. 1 and a partially broken away base of a drinking bottle in 2 is for illustrative purposes only and forms no part of the claimed design.
